CONTINUOUS DRIER FOR WET GRANULAR MATERIAL

William H. Golden, Pittsburgh, Pa.

Application June 24, 1937, Serial No. 150,048
Renewed September 19, 1939

9 Claims. (Cl. 34—34)

This invention relates to driers for wet granular material such as wet sand and the like, and more particularly to driers adapted for continuous operation. Objects of the invention are 5 to provide a drier of this nature which will provide a more intimate heat exchange contact between the sand or other material to be dried and the heating medium, and which will have a higher drying capacity than other devices of this 10 nature now in use.

A further object of the invention is to provide a drier which will bring the sand or other material to be dried in contact with heated surfaces in the form of a number of relatively thin films 15 thereby promoting drying speed and permitting the ready escape of water vapor from the material.

A still further object of the invention is to provide a drier which is simple in construction, 20 efficient in operation, and in which the drying elements consist of a number of superposed trays which are interchangeable and readily replaceable. Further objects will become apparent 25 from the following description and will be pointed out in the claims appended thereto.

With the above and other objects in view, the 30 invention consists in the novel combination and association of parts as will be hereinafter more particularly described, reference being had to the accompanying drawing.

In the drawing:

Fig. 1 is a vertical section showing the assembly 35 of a drier constructed in accordance with the invention.

Figs. 2, 3 and 4 are horizontal sections on the 40 lines X—X, Y—Y, and Z—Z, respectively, of Fig. 1, looking in the direction of the arrows. Fig. 5 is a detail section taken on the line 5—5 of Fig. 3 showing one of the drying trays.

Referring to Fig. 1, the drier includes a furnace 1, having a central flue 2, and plurality of 45 spaced side flues 3, the whole constituting an assembly for the generation and transmission of heat. The furnace 1 may be a coal burner as shown, but it may be readily adapted for the combustion of wood, oil, or gas without departing from the scope of the invention. In the modification shown the furnace consists of a supporting base 4, an ash box 5, provided with an opening 6 for the removal of ashes and preferably fitted in the usual manner with an ash door having an air register and a top flange 7 supporting a grate 8. The fire box consists of a cylindrical side wall 9, which may be lined with insulating brick and which is provided with an outwardly extending flange 10 at the lower edge thereof for a purpose which will subsequently be described. A firing door 11 is fitted into the side wall in the usual manner but is fitted with 55 a firing collar 12 extending some distance away

from the furnace to keep the sand or other material to be dried out of the fire box.

The furnace 1, whether of the coal, oil, or gas fired type is provided with a fire box dome or top 13 which is seated on the cylindrical side 5 wall and is provided with the central flue 2 and the side flues 3, which are preferably four in number, spaced at angles of 90°. In the modification shown, the dome 13 is a separate casting, and is fitted with flanges 14 to make a gas-tight fit with the side wall 9 and the flues are cast integral therewith. The central flue 2 is relatively short and has a level upper edge, while the side flues 3 are beveled toward the central flue and provided with notches 4 for a purpose 10 15 which will subsequently be described.

The drying trays which are mounted above the furnace in superposed relation constitute one of the features of the invention, since they operate to bring the sand or other material to be dried 20 into close contact with the flues containing the hot gases from the furnace. Each tray consists as shown in Fig. 5 of an inverted frusto-conical bell 15 which is preferably of cast metal, the bell having a peripheral zone consisting of a heat conducting flange 16 with openings 17 therein and a central zone, which is also preferably provided with additional openings 18 and which has a plurality of vertical flue pipe sections 19 cast integral therewith. In the top of each flue 25 pipe section 19 is a small vent 21 which is of the order of 0.5 sq. in. in cross-section and which provides communication between the interior of the flue and the spaces between the drying trays. Similar vents may be provided in the central 30 flue pipe sections 20, although they are not shown on the drawing.

Reference to Fig. 1 of the drawing will show that the various sections are supported upon each other when the drier is assembled so that any section may be removed and a new one replaced with a minimum of time and effort. Similarly, the drier may be provided with any number of 35 drying trays to suit the requirements of any given sand or other material to be dried and the extent to which the moisture must be removed.

It will be noted that the peripheral openings 40 45 50 55 17 are larger than the central openings 18, thereby promoting the continuous movement of the sand or other material from the periphery of the trays to the central zone and causing it to be heated in thin films which promotes a ready escape of the steam or water vapor between the trays and through the vents 21 in the flue pipe sections 19.

The various drying tray sections are covered by a top flue piece 25, which is in the form of a spider seated on the top flue pipe sections as at 60 65 70 75 80 85 90 95 26 and having beveled edges to correspond therewith. The arms of the spider which constitute

continuations of the flue pipe sections connect them with a stack 21, preferably provided with a damper 28, and thus serve to collect all the hot gases from the furnace 1.

5 The entire drier assembly is surrounded by a vertical shell 30 which is supported by a perforated ring 31 seated on the flange 10 at the bottom of the furnace wall. This shell serves to retain the sand and conduct the dried sand downwardly around the wall 9 of the fire box and through openings 32 in the ring 31 and away from the drier.

10 The operation of my improved drier will be apparent from the above description. Sand is shoveled into the top of the drier, and is distributed over the top bell by the arms of the spider 25. The sand travels by gravity over the surface of the top drying tray and falls through the openings 17 and 18 onto the second tray in

15 the form of relatively thin streams, the moisture being removed by the heat of the tray and of the flues 19 and 20 around which the sand is caused to pass. The sand drops by gravity from tray to tray, losing moisture in each passage over the hot metal. The openings 17 and 18 are preferably made smaller in the lower trays than are the corresponding openings in the upper trays, and are sized so that the bells or trays do not completely fill with sand. The openings

20 21, being at the tops of the flue sections always remain uncovered so that moisture evaporated from the sand will pass into the combustion gas flues and will be carried away with the combustion gases therein. By reason of the inclined surfaces of the trays and the heat conducting capacity of the flanges 16, only dry sand can come into contact with the top or side walls of the furnace 1, and so these parts are protected from warping or cracking.

25 40 From the above it will be seen that the invention provides a drier which is both simple and efficient in operation. I have found by actual comparison that the drier of the present invention will remove the same amount of moisture from 50% more sand than will other driers of equal size that are now on the market.

45 What I claim is:

1. A continuous drier for wet granular material comprising in combination a plurality of superposed, inverted frusto-conical drying trays, openings near the periphery of each tray to permit the gradual downward passage of the granular material from tray to tray, and a vertical heating conduit passing through the central zones of said trays.

50 55 60 2. A continuous drier for wet granular material comprising in combination a plurality of superposed, inverted frusto-conical drying trays having graduated openings therein of a size to permit the gradual downward passage of the granular material from tray to tray, a shell surrounding said trays, and a plurality of vertical heating conduits passing through the central zones of said trays.

65 70 75 3. A continuous drier for wet granular material comprising in combination a plurality of superposed, inverted frusto-conical drying trays, openings near the periphery of each tray to permit the gradual downward passage of the granular material from tray to tray, a vertical flue for hot gases passing through the central zones of said trays, and vents in said flue between each pair of trays to permit water vapor evolved from the granular material to pass into the flue.

4. A continuous drier for wet granular material comprising in combination a plurality of superposed, inverted frusto-conical drying trays having graduated openings therein of a size to permit the gradual downward passage of the granular material from tray to tray, a shell surrounding said trays, a plurality of vertical flues for hot gases passing through the central zones of said trays, and vents in said flues between each pair of trays to permit water vapor evolved from the granular material to pass into the flue.

5 10 15 5. As an article of manufacture, a drying tray comprising an inverted frusto-conical bell of cast metal, said bell having a peripheral zone consisting of an apertured heat-conducting flange and a central zone having openings therein and a plurality of vertical flue pipe sections cast integral therewith.

20 25 6. As an article of manufacture, a drying tray consisting of an inverted frusto-conical bell of cast metal, said bell having a peripheral zone consisting of a heat conducting flange with openings therein and a central zone having openings therein and a plurality of vertical flue pipe sections cast integral therewith, each pipe section having a notched upper edge that terminates in a plane parallel to the plane of the bell at its base.

30 35 7. A continuous drier for wet granular material comprising a plurality of drying trays, each tray comprising an inverted frusto-conical bell of cast metal having a peripheral zone consisting of a heat conducting flange with openings therein to permit the passage of the granular material and a central zone having openings therein and a plurality of vertical flue pipe sections surrounding said openings, each pipe section having a notched upper edge that terminates in a plane parallel to the plane of the bell 40 at its base and forms a supporting seat for the tray above it, and a top flue piece comprising a spider seating on the top flue pipe sections and connecting them with a stack.

45 50 55 8. A continuous drier for wet granular material comprising in combination a furnace for the generation of hot gases, a plurality of vertical flues in the top of said furnace, a plurality of superposed, inverted frusto-conical drying trays surrounding said flues, openings near the periphery of each tray of a size to permit the gradual downward passage of the granular material from tray to tray, vents in said flues between said drying trays, and a spider seating on the tops of said flues and connecting them with a stack.

60 65 70 75 9. A continuous drier for wet granular material comprising in combination a furnace including a cylindrical side wall, having an outwardly extending flange at the bottom thereof, a perforated ring seated on said flange, a cylindrical shell supported on said ring, a top for the furnace seated on the cylindrical side wall thereof and provided with a central flue and a plurality of spaced side flues having notched upper edges which are beveled toward the central flue, a plurality of drying trays comprising inverted frusto-conical bells seated upon said flues, each bell having graduated openings therein and notched flue sections in alignment with the 70 flue sections of the furnace top, and a collecting spider surmounting the top flue sections and connecting them with a stack.
